UNITED STATES PATENT OFFICE.

CHARLES BARRINGTON, JR., OF LOS ANGELES, CALIFORNIA.

GAS-REGULATOR.

1,104,865.

Specification of Letters Patent. Patented July 28, 1914.

Application filed December 30, 1913. Serial No. 809,560.

To all whom it may concern:

Be it known that I, CHARLES BARRINGTON, Jr., a citizen of the United States, residing at Los Angeles, in the county of Los Angeles 5 and State of California, have invented new and useful Improvements in Gas-Regulators, of which the following is a specification.

This invention relates to gas regulators 10 whereby the pressure or head of gas provided at the point of consumption or in the service pipe may be controlled, automatically, and thus be maintained even and consistent at predetermined pressure.

15 The present invention has for its object to aspects, comprises a further development of certain types of gas regulators such as more particularly disclosed in U. S. Letters Patent No. 1,058,102, issued to James R. Rick- 20 etts, assignor, April 8, 1913, and in an application filed by me April 4, 1913, Serial No. 758,810, which application was allowed July 10, 1913.

The present invention has for its object to 25 provide improvements in gas regulators of the general types and constructions disclosed in and by said mentioned patent application, which will be superior in point of relative simplicity and inexpensiveness of 30 construction and organization combined with positiveness and reliability and efficiency in service, sensitive responsiveness to variations in working conditions, and facility of adjustment and repair and replacement of parts, and capability of long 35 continued operation or use without attention.

With the above and other objects in view, the invention consists in the novel provision, 40 formation, construction, combination, association and relative arrangement of parts, members and features, all as hereinafter described, shown in the drawings, and finally pointed out in claims.

In the drawings:—Figure 1 is a trans- 45 verse vertical sectional view, parts being in elevation, of a gas regulator constructed and organized to exemplify one embodiment of the invention; Fig. 2 is a horizontal trans- 50 verse sectional view of the same, taken upon the line x^2-x^2 , Fig. 1, and looking in the direction of the appended arrows; Fig. 3 is an enlarged fragmentary and partially verti- 55 cally sectioned view of certain features of the gas feed control means shown in Figs. 1 and 2; and Figs. 4 and 5 are enlarged per-

spective views of detached features of said gas feed control means.

Corresponding parts in all the figures are designated by the same reference characters.

Referring with particularity to the drawings, the improved gas regulator comprises in the main a casing A within which is suitably held a transverse diaphragm B, the casing A preferably comprising a circular top member 6 and a circular bottom member 65 7 having co-engaging edge flanges 8 between which the diaphragm is gripped and held at its edges. A weight 9 and a bracket 10 are held to the diaphragm respectively above and beneath the same by a screw or the like 70 11, applied centrally of the diaphragm, and the bracket ranges downwardly within a radial bottom extension 12 of the bottom casing member 7, at the outer open end of which is provided a detachable closure C. 75 A gas main pipe 13 and a gas service pipe 14 are connected with suitably threaded nipples 15 and 16 formed or provided upon the extension 12 at the bottom and top thereof just within the open end thereof which is 80 normally sealed by the closure C.

The top member 6 of the casing is provided with an upwardly projected centrally disposed nipple 17 within which is screwed a threaded plug 18 perforated to prevent air 85 cushion within the casing A above the diaphragm, compression means D being thus adjustably held between the center of the diaphragm B, or the weight 9 thereof, and such plug 18. 90

E designates gas feed control means arranged within the casing A and the extension 12 thereof, and carried upon the closure C, being detachable in entirety from the bracket 10 through which such means normally co-operate with the diaphragm. Such gas feed control means operate with respect to a port 19 formed in a plug 20 screwed into a threaded opening in the casing extension 12 registering with the nipple 15 of the gas main 100 pipe 13.

A description will now be given of the gas feed control means and the construction whereby the same are mounted upon the closure C and are associated with the dia- 105 phragm B.

The closure C comprises a flat plate 21 suitably bolted as at 22 to the outer open end of the casing extension 12, and having inwardly projecting spaced brackets 22^a in 110

the free extremities of which is mounted an adjustable shaft 23 which passes removably through openings in spaced cheeks 24 adjacent to the inner end of an oscillating arm 25 the other end of which is received adjustably within an enlarged opening 26 in the bracket upon the diaphragm. The oscillating arm thus ranges longitudinally of the casing extension 12, between the cheeks 24 of which a depending head 27 upon a regulating arm 28 of adjacent means *e* receives the detachable shaft 23 through a suitable opening, the regulating arm 28 thus being capable of oscillation jointly with and relatively to the oscillating arm 25, upon the shaft 23. The end portion of the regulating arm 28 nearest to the closure C is bifurcated, as at 29, to freely receive and permit freely to play the upper reduced end 30^a of a valve stem 30 mounted to play longitudinally, or vertically of the casing extension 12, in spaced superposed guides 31 and 32 provided upon the brackets 22 and directed transversely therefrom between and at right angles thereto. The stem 30 carries at its lower end a valve head 33 to which is held a compressible facing 34, by a flanged cap 35 detachably held to the head 33 by a cotter pin 36 passed through registering perforations in the head and the cap 35. A cotter pin 37 is passed through the stem 30^a above the forked end 29 of the regulating arm 28, loosely and operatively holding the stem to the regulating arm. The facing 34 seats upon the plug 20 at the orifice of the gas port 19. The other end of the arm 28 is adjustably and operatively connected with the oscillating arm 25 so that the shaft 23 is between the same and the stem 30, by a pin 38 having an enlarged threaded portion 39 threaded into the regulating arm 28 and projecting loosely through an elongated vertical slot 40 in the oscillating arm 25, and having its lower end headed over as at 41 to hold the parts in working relation. The pin 38 is slotted at its upper end, as at 42, to receive an adjusting implement, which may be passed to it through an opening normally closed by a screw plug 43, in the top of the casing extension 12.

The operation, method of use and advantages of the improvements in gas regulators constituting the invention will be readily understood from the foregoing description, taken in connection with the accompanying drawings and the following statement:—Gas flows to the chamber within the casing A beneath the diaphragm B through the gas main pipe 13, and the gas port 19, as permitted by the gas feed control means E, and the gas, thus regulated in its flow by the gas feed control means, coöperating with the diaphragm, passes out from the casing through the service pipe 14. When the parts are in

the working positions shown in the drawings, the shaft 23 is confined and kept in place by the walls of the casing extension 12; and the valve stem 30 with its head 33 and connected parts, and the oscillating arm 25 and regulating arm 28, and connected parts, are all introduced within the casing through the open end of the extension 12, the inner end of the arm 25 freely entering the opening in the bracket 10. The closure plate 21 is then bolted to the casing. The facing 34 on the valve head is normally slightly spaced from the gas port plug 20, and an increase in gas pressure raises the diaphragm, swinging the arms 25 and 28, and bringing the valve head face closer to its seat at the orifice of the gas port. Decreasing pressure causes increase of this space, permitting more gas per time unit to pass through the regulator. The normal spacing of the valve head from its seat may be varied by adjustment of the regulating arm pivotally upon the shaft 23, by turning the threaded pin 38.

If it is desired to remove the facing 34, for repair or substitution, the cotter pin 36 is withdrawn, the means *E* being withdrawn from the casing, or partially withdrawn, the cap 35 is slipped off from the valve head, and the facing 34 thus removed. By removing the cotter pin 37 the valve head and its stem 30 may be slipped from the guides 31 and 32. The forked formation at 29 permits the regulating arm 28 to rock while the valve stem 30 plays vertically. The pin 38 rocks slightly in the elongated slot 40 in the oscillating arm 25, to accommodate relative pivotal movement of the regulating arm and the oscillating arm as the former is adjusted in utilizing the adjusting means *e* as above set forth. These arms may be disconnected by filing or chipping off the head 41 at the lower end of the pin 38. The means *E* may be withdrawn from the diaphragm and the casing without disturbing the gas main and service pipes.

The construction and combination of features described permit of positiveness and sensitiveness of operation, and obviate the necessity of frequent repair, adjustment and replacement of parts, which, as will be noted, may be conveniently and expeditiously performed.

I do not desire that my invention be limited in its interpretation to any specific features of construction and arrangement, by reason of the disclosure in the specification and drawings of an exemplary embodiment of the invention.

Having thus disclosed my invention, I claim and desire to secure by Letters Patent:—

1. A gas regulator, comprising a casing having a gas inlet port and outlet opening and a diaphragm within the casing, gas

feed control means within the casing and operatively connected with said diaphragm, said casing being provided with an opening; and a closure detachably applied to 5 said opening and with which said gas feed control means are connected for passage through said last named opening; said closure being provided with supporting means for said gas feed control means normally projecting within the casing, said supporting means comprising two pairs of spaced brackets, and said gas feed control means comprising an oscillating arm detachable from the diaphragm and pivotally connected with one pair of said brackets, and a valve for the gas inlet port actuated by said oscillating arm and guided in its 10 movement by the other pair of said brackets. 15

2. A gas regulator, comprising a casing 20 having a gas inlet port and outlet opening and a diaphragm within the casing, gas feed control means within the casing and operatively connected with said diaphragm, said casing being provided with an opening; and a closure detachably applied to 25 said opening and with which said gas feed control means are connected for passage through said last named opening; said closure being provided with supporting means for said gas feed control means normally projecting within the casing, said supporting means comprising two pairs of spaced brackets, and said gas feed control means comprising an oscillating arm detachable from the diaphragm and pivotally connected with one pair of said brackets, and a valve for the 30 gas inlet port actuated by said oscillating arm and guided in its movement by the other pair of said brackets; and a regulating arm likewise pivotally connected with said brackets with which said oscillating arm is 35 pivotally connected and loosely connected with said valve; said regulating arm being provided with a threaded pin passed loosely through said oscillating arm and whereby said regulating arm and said valve may be 40 adjusted. 45

3. A gas regulator, comprising a casing 45 having a gas inlet port and outlet opening and a diaphragm within the casing, gas feed control means within the casing and operatively connected with said diaphragm, said casing being provided with an opening; and a closure detachably applied to 50 said opening and with which said gas feed control means are connected for passage through said last named opening; said closure being provided with supporting means for said gas feed control means normally projecting within the casing, said supporting means comprising two pairs of spaced brackets, and said gas feed control means comprising an oscillating arm detachable from the diaphragm and pivotally connected with one pair of said brackets, and a valve for the 55 gas inlet port actuated by said oscillating arm and guided in its movement by the other pair of said brackets; and a regulating arm likewise pivotally connected with said brackets with which said oscillating arm is pivotally connected and loosely connected with said valve; said regulating arm being provided with a threaded pin passed loosely through said oscillating arm and whereby said regulating arm and said valve may be 60 adjusted; said 65

connected with said brackets with which said oscillating arm is pivotally connected and loosely connected with said valve, said regulating arm having a bifurcated end portion receiving a portion of said valve, said valve being provided with detachable means holding the valve to said regulating arm. 70

4. A gas regulator, comprising a casing 75 having a gas inlet port and outlet opening and a diaphragm within the casing, gas feed control means within the casing and operatively connected with said diaphragm, said casing being provided with an opening; and a closure detachably applied to said opening and with which said gas feed control means are connected for passage through 80 said last named opening; said closure being provided with supporting means for said gas feed control means normally projecting within the casing, said supporting means comprising two pairs of spaced brackets, and said gas feed control means comprising an oscillating arm detachable from the diaphragm and pivotally connected with one pair of said brackets, and a valve for the 85 gas inlet port actuated by said oscillating arm and guided in its movement by the other pair of said brackets; and a regulating arm likewise pivotally connected with said brackets with which said oscillating arm is 90 pivotally connected and loosely connected with said valve; said regulating arm being provided with a threaded pin passed loosely through said oscillating arm and whereby said regulating arm and said valve may be 95 adjusted. 100

5. A gas regulator, comprising a casing 105 having a gas inlet port and outlet opening and a diaphragm within the casing, gas feed control means within the casing and operatively connected with said diaphragm, said casing being provided with an opening; and a closure detachably applied to said opening and with which said gas feed control means are connected for passage through 110 said last named opening; said closure being provided with supporting means for said gas feed control means normally projecting within the casing, said supporting means comprising two pairs of spaced brackets, and said gas feed control means comprising an oscillating arm detachable from the diaphragm and pivotally connected with one pair of said brackets, and a valve for the 115 gas inlet port actuated by said oscillating arm and guided in its movement by the other pair of said brackets; and a regulating arm likewise pivotally connected with said brackets with which said oscillating arm is pivotally connected and loosely connected with said valve; said regulating arm being provided with a threaded pin passed loosely through said oscillating arm and whereby said regulating arm and said valve may be 120 adjusted; said 125

pin being headed exteriorly of said oscillating arm.

6. In a gas regulator, a casing provided with a gas inlet port and a gas outlet opening and with an interiorly arranged diaphragm; and gas feed control means operating with respect to said gas inlet port and comprising an oscillating arm detachably connected with the diaphragm, a regulating arm, said arms having a common pivotal center, a valve operatively connected with said regulating arm, and a pin threaded to said regulating arm and passed loosely through an opening in said oscillating arm and having a head exteriorly of said oscillating arm holding said arm in adjustable relation.

7. In a gas regulator, a casing provided with a gas inlet port and a gas outlet open-

ing and with an interiorly arranged diaphragm; and gas feed control means operating with respect to said gas inlet port and comprising an oscillating arm operatively connected with said diaphragm, a regulating arm operatively connected with said oscillating arm, and a valve for the gas inlet port; said valve and said regulating arm being provided one with a fork and the other with detachable means whereby said valve and regulating arm are held together. 20 25 30

In testimony whereof, I have signed my name to this specification in the presence of two subscribing witnesses.
